F. J. WOOD

WATER HEATER ATTACHMENT FOR FURNACES

Filed March 10, 1924

Inventor
Tracy J. Wood
by Davis & Hague, Atty's.

UNITED STATES PATENT OFFICE.

FRANZ J. WOOD, OF DES MOINES, IOWA.

WATER-HEATER ATTACHMENT FOR FURNACES.

Application filed March 10, 1924. Serial No. 698,344.

This invention relates to improvements in means for heating water for hot water supply for domestic purposes.

The object of my invention is to provide an improved device for supplying hot water to what is commonly known as the hot water boilers or tanks, the said device being of simple, durable and inexpensive construction and so arranged and constructed that it may be easily and quickly applied to the furnace of the ordinary house heating system, which may be either steam or hot water or similar system, and when applied the device will very rapidly and economically heat the water.

More specifically it is the object of my invention to provide a heating unit having a comparatively large amount of heating surface and adapted to be placed into a house heating furnace of the ordinary type through the fuel door, the device being so arranged that when applied water may be made to circulate through the device and to be heated by the fuel within the furnace. The device being provided with connections so arranged that the circulating water from the heater may be made to either circulate through an auxiliary water tank or through the house heating system at the will of the operator. The device is to be preferably used with that type of furnaces which employs a liquid fuel burner.

My invention consists in the construction, arrangement and combination of the various parts of the device, whereby the objects contemplated are attained, as hereinafter more fully set forth, pointed out in my claims, and illustrated in the accompanying drawings, in which:

Figure 1 is a side elevation of my improved device showing the manner in which it is connected to a hot water tank, and also showing the manner in which it is mounted in the heating system, the heater of the said system being shown in section.

Figure 2 is a horizontal sectional view taken on the line 2-2 of Figure 1.

The numeral 10 indicates the hot water tank of the ordinary construction mounted on a supporting base 11. The tank 10 is provided with an outlet pipe 12 and an inlet pipe 13 which are connected to the water pipe system of a dwelling. The tank 10 is also provided with an inlet circulating pipe 14 and an outlet circulating pipe 15 which

are also of the usual construction and arrangement.

The numeral 16 indicates a hot water heated which may be of any of the ordinary types in common use or it may be of the steam or vapor type. The heater 16 is provided with water compartments 17, a door opening 18 and a fuel burner 19. The burner 19 is preferably of that type designed to burn liquid fuel such as kerosene or distillate, and preferably of that type which may be automatically and manually controlled from the living room of the dwelling. Burners of this type are usually placed in about the same position that the grates of a coal burning furnace would assume.

The heater is provided with the usual water heating coil 20 which comprises a U-shaped pipe extending into the fire box of the furnace, having one end of the said pipe connected with the inlet pipe 14 of the hot water supply tank, and its opposite end connected with the outlet pipe 15 by means of suitable elbows 21 and laterally extending pipe portions 22. The coil 20 together with the pipes 14 and 15 are substantially of the ordinary construction. The coil 20 is placed in the fire box in the usual manner and provides means whereby under certain conditions the tank 10 is supplied with hot water in the usual manner.

This arrangement is sufficient to give plenty of hot water under ordinary conditions during the winter months while the heater is being continuously used. To provide means for supplying hot water for laundry purposes and the like during the summer months when the heater 16 is not being used, I have applied an auxiliary water heating element which I have placed in the furnace of the heater 16 in such a manner that the burner 19 may be employed to heat the water in the tank 10.

My improved device comprises a metal casing 23 formed hollow and of such shape and dimensions as to substantially fill the fuel door of the furnace. The said casing 23 is provided with a back wall 24, a front wall 25, a top 26, a bottom 27 and end walls 28. The back 24 is drilled and tapped with two rows of openings 29 and 30. The openings 29 extend near the top member 26 and the openings 30 just above the bottom member 27. The openings 29 and 30 are designed to receive the ends of the pipes 31

which extend horizontally into the furnace fire box, and have their inwardly extending ends provided with elbows 32 connected by a vertically arranged pipe 33.

5 The wall 25 is provided with an outwardly extending pipe 34 having a T 35 provided with an upwardly extending pipe 36 in which is mounted a union 37 and a cut-off valve 38 above the said union. The upper end of the pipe 36 is provided with an elbow 39 and an inwardly extending pipe 40, the inner end of which is in communication with the water compartments 17. The T 35 is also provided with an outwardly extending pipe 41 in which is a union 42 and a cut-off valve 43. The pipe 41 is connected to a T 44 included in the pipe 14.

The front wall 25 is also provided with an outwardly extending pipe 45 which includes 20 a T 46 a union 47 and a cut-off valve 48. The union 47 is between the T 46 and the valve 48. The outer end of the pipe 45 is connected to a T 49 in the pipe 15. The T 46 is provided with a downwardly extending pipe 50 in which is included a union 51 and a cut-off valve 52. The downwardly extending end of the pipe 50 is provided with an elbow 53 and an inwardly extending pipe 54 which is also in communication with the 25 water compartments 17 at a point near the bottom of said compartments.

By this arrangement it will be seen that I have provided a water heating attachment which may be mounted in the door opening 35 of a furnace with the heating pipes 31 extending into the combustion chamber.

It will be seen that the pipes 31 are in communication with the tank 10 by means of the pipes 15 and 45, the compartment 17, 40 the pipes 34 and 41 and the pipe 14. It will also be seen that if fuel from the burner 19 is ignited the heat from the said fuel will heat the water within the pipes 31, causing the circulation through the pipes 45 with the water in the casing 23. The heated water in the casing 23 will flow outwardly through the pipes 34, 41 and 14 to the upper end of the tank 10, permitting the cold water from the bottom of the tank 10 to 50 pass through the pipes 15 and 45. It will be seen that this circulation will be continuous as long as the burner 19 is in operation, and on account of the coils 31 being placed in position immediately above the burner, 55 as clearly shown in the drawings, a very small amount of the heat from the burner will be taken up by the water from the compartments 17, and that in a few minutes time the water in the tank 10 will be 60 come sufficiently hot for whatever purpose it is desired, at which time the fuel of the burner 19 is turned off, which provides means whereby the burner of the furnace, which is already installed, may be utilized 65 for the purpose of supplying heat for hot

water for any purpose desired, without the expense of an additional burner or controlling mechanism.

By providing the unions 37, 42, 47 and 51 I have provided means whereby the heating unit may be easily and quickly attached or detached, and may be entirely removed from the furnace during the winter months if desired, or any time when the furnace is continuously operated; or by closing the 70 valves 43, and 48 and leaving the heater attachment in the furnace and opening the valves 38 and 52, I have provided means whereby the water in the member 23 will be brought into communication with the 80 compartment 17 and a complete water circulation will be established through the coils 31, the hot water from said coils being delivered to the compartment 17 and caused to enter the regular heating system. 85

This provides an arrangement which is very desirable even during the winter months while the furnace is being continuously operated, and especially in the spring and fall. When it is desired to use a comparatively large amount of water from the tank 10 for washing purposes, under ordinary circumstances but a very small portion of the water in the tank 10 will be heated. It will be seen that the valves above referred to may be easily and quickly adjusted to place the coils 31 in direct communication with either the compartment 17 or the tank 10. If the coils are in communication with the tank 10 for the purpose above stated, the coil 31 may also be left in communication with the tank until sufficient amount of hot water is provided for said tank, after which the water in the coils 31 may be placed into the compartment 17 105 and all of the heat from the burner 19 utilized economically.

It will also be seen that this device could be applied to the ordinary coal burning furnace, it only being necessary to provide an 110 additional opening in which to place the member 23.

I claim as my invention:

1. In combination, a hot water furnace having a fuel door opening, a hot water 115 supply tank, an auxiliary heating unit detachably mounted in said door opening and extended within the combustion chamber of said furnace, means for communicating said heating unit with said supply tank or with the water compartment of said furnace, said communicating means including means whereby the said heating unit may be quickly detached therefrom.

2. In combination, a hot water furnace 120 having a fuel supply opening and a water compartment, a hot water supply tank, a heating coil for said furnace in communication with said supply tank, an auxiliary heating element detachably mounted in said 125

fuel supply opening and extended into the combustion chamber of said furnace, pipes for communicating said heating element with said water supply tank, pipes for communicating said heating element with the water compartment of said furnace, all of said pipes including unions whereby the said auxiliary heating element may be easily and quickly detached.

10 3. In combination, a hot water furnace having a fuel supply opening and water compartment, a hot water supply tank, a heating coil for said furnace in communication with said supply tank, an auxiliary heating element detachably mounted in said fuel supply opening and extended in the combustion chamber of said furnace, means for communicating said auxiliary heating element with said hot water supply tank, means for communicating said auxiliary heating unit with the water compartment of said furnace, said communicating means being adapted to communicate said auxiliary unit with either the hot water supply tank or the water compartment of said furnace at the will of the operator including means whereby the auxiliary heating element may be quickly detached, and means for applying heat to said coils.

30 4. In combination, a hot water furnace having a hot water compartment, a fuel door opening and a heating element extending into the fire pot of said furnace, a hot water supply tank, said tank being provided with an inlet and outlet circulating pipe, a casing having a water chamber detachably mounted in the said door opening, a series of pipes extending inwardly from said chamber, and in communication therewith, into the combustion chamber of said furnace above said heating unit, an outlet pipe for said water chamber in communication with the inlet pipe of said supply tank, a valve and a union for said outlet pipe, a pipe in communication with said outlet pipe and

in communication with the water compartment of said furnace, a valve and a union for the last said pipe, an inlet pipe for said water chamber in communication with the outlet pipe of said water chamber in communication with the outlet pipe of said water supply tank, a valve and a union for the last said inlet pipe, a pipe in communication with the last said inlet pipe and in communication with the said water compartment of said furnace, and a valve and a union for the last said pipe.

5 5. A detachable heating unit for furnaces of the class described comprising a casing having a water chamber, a series of heating pipes in communication with said chamber, said casing being adapted to fit and rest in the door opening of a furnace, an outlet pipe for said casing including a T and a valve, a branch pipe for said T, said branch pipe also being provided with a valve, said casing member also being provided with an inlet pipe having a valve and a T, said second T being provided with a branch pipe and said branch pipe having a valve, for the purposes stated.

6 6. In combination, a hot water furnace having a fuel door opening, a hot water supply tank, an auxiliary heating unit designed to fit and be detachably mounted in said door opening having heating members extending into the combustion chamber of said furnace, and means for communicating said heating unit with either the water compartment of said furnace or with said supply tank.

7 7. In combination, a hot water furnace having a fuel door opening, a hot water supply tank, an auxiliary heating unit designed to fit and be detachably mounted in said door opening, and means for communicating said heating unit with either the water compartment of said furnace or with said supply tank.
